CLAIM

The ornamental design for a bag as shown and described.

DESCRIPTION

FIG. 1 is a perspective view of a bag;

FIG. 2 is a perspective, partially exploded view thereof;
FIG. 3 is a front side elevation view of the bag as shown in FIG. 1;

FIG. 4 is a rear side elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The shorter, lighter dashed broken lines shown in the drawings depict portions of the Bag that form no part of the claimed design. The longer, heavier dashed broken lines shown in the drawings depict stitching and form no part of the claimed design. The cross patterns shown in the drawings are not features of the design, but are utilized to depict surface texture. The surface shading lines show contour and/or distinguish between open and solid areas. The surface shading lines are not surface ornamentation.
